(57) **CLAIM**

The ornamental design for a vertical ladder movable to an inclined position, as shown and described.

DESCRIPTION

FIG. 1 is a perspective view of a vertical ladder movable to an inclined position embodying our new design; FIG. 2 is a side elevational view thereof; FIG. 3 is a front elevational view thereof; and, FIG. 4 is a top plan view thereof. The broken lines are for illustrative purposes only, and form no part of the claimed design.
